 Rhode Island

Application May 16, 1947, Serial No. 748,631

5 Claims. (Cl. 137—157)

1

This invention relates to valves for the control of fluids and more particularly to pressure retention or sealing mechanism for motor driven reciprocating members which are displaced in accordance with variations in the value of a power medium.

As is known, the diaphragm type of valve comprises essentially a diaphragm and spring means associated with the valve element such that the element is urged in one direction by the spring and in the opposite direction by fluid pressure acting on the diaphragm. Such valves may be of the direct or reverse acting type. In the direct acting valves the valve element is moved downwardly by the pressure of air or other fluid medium in the upper diaphragm case and is returned by the spring. Conversely, in the reverse acting type the valve is urged downwardly by the spring and fluid pressure is exerted in the lower diaphragm case to elevate the valve element.

A major desideratum in such structures is a high sensitivity of response to very small increments of air pressure applied to the diaphragm. Such high sensitivity has not heretofore been satisfactorily achieved. The earlier structures in the art were characterized by a marked hysteresis or failure to translate very small changes in air pressure into a corresponding displacement of the valve element. This lack of sensitivity is inherent in the nature of the prior valve constructs. Inasmuch as the accuracy of control ultimately effected by the valve element is a function of the variation in air pressure in a diaphragm chamber, it is apparent that the reciprocation of the rod or stem, which is connected to the valve element, should be secured with the absolute minimum of friction. Such a low friction reciprocation, of course, is difficult to achieve in even simple mechanisms but is particularly difficult to attain under circumstances encountered in the diaphragm type of valve of the reverse acting type, i. e., where there is imposed the necessity of establishing a highly effective air seal between the lower diaphragm chamber and the reciprocating stem.

In the past, various expedients have been invoked to establish an effective fluid seal and to reduce the friction of the valve stem to thereby increase the sensitivity of the valve unit. Generally considered, these efforts have involved the use of special packing glands, oil impregnated porous metal bushings and the like. In many prior structures where an effective air pressure seal was desired recourse was had to metal bellows seals. Where frictionally engaging contact

2

seals were employed the direct sliding contact with the reciprocating member inexorably set up substantial frictional resistance to the reciprocation of the stem. Similarly, where metal bellows were utilized not an inconsiderable component of the applied force was expended in extending or compressing the metallic structure of the bellows.

As a result of extensive experimentation on this problem it has now been found that the operation of motor valve structures of the type described may be markedly improved by increasing the sensitivity of the valve to minor increments of air pressure change and by insuring a quick or immediate response to such pressure changes.

The improvements achieved by the present invention stem from the concept of substantially eliminating contact or frictional seals and establishing a gas seal between the diaphragm casting and a reciprocating valve member by means of a non-metallic bellows seal. As will be seen more fully hereinafter, the novel sealing means comprises a flexible non-metallic member such as a suitable fabric coated or impregnated with an elastomer such as natural or synthetic rubbers or the like. Such material, as will readily be appreciated, is flexible or flaccid and can be extended with but the minimum amount of resistance particularly when in corrugated form. The resistance set up by the flexible fabric will vary with the type of the fabric and particularly with its thickness. In order to insure high sensitivity a highly flexible, gas impermeable fabric is utilized as a bellows and the fabric itself is re-enforced and maintained in its desired configuration by means of a steel spring.

In order to enable a more ready comprehension of the invention there is shown in the accompanying drawing an illustrative preferred modification of the novel seal as embodied in a valve reversible superstructure, in which:

Fig. 1 is a central vertical section of a diaphragm valve superstructure, and

Fig. 2 is an enlarged sectional detail of the novel sealing means.

In order to simplify the description of the invention the improved type of seal is illustrated as embodied in the superstructure for a valve body, it being understood that any suitable type of valve body in which fluid flow is to be controlled may be attached to such standard superstructure. While the novel low inertia and low friction sealing connection may be utilized generally in diaphragm valves, it is shown herein

as embodied in a standardized reversible superstructure, that is to say, one which may be associated with either a direct or reverse acting valve unit without any change in the motor casting and the associated spring case or barrel.

As will be seen more fully hereinafter, the valve superstructure comprises essentially a motor provided with a novel type of seal and a connected reciprocating stem with spring means associated therewith. The reciprocating stem is moved in one direction in response to variations in the value of the power medium admitted to the motor and is constantly urged in the opposite direction by the spring means.

As shown in the drawings, the superstructure comprises a motor, designated generally by the numeral 1, which is provided with the reciprocating stem 2 centrally positioned and operable in the spring barrel or case 3. The spring case contains the spring 4, which is so constructed and arranged as to apply a force to the stem opposing the action of the diaphragm. As will appear subsequently, by simple and conveniently effected change in the position of certain parts associated with the spring its direction of thrust can be reversed so that, as intimated previously, the superstructure can function equally effectively with a direct or reverse acting valve unit.

The spring barrel is extended downwardly to form the integral vertically slotted yoke 5. This latter is formed with the terminal flange 6 which may be provided with apertures for reception of studs or bolts so that the entire superstructure can readily be attached directly to a valve body or to an intermediate bonnet of a valve body.

Considered more in detail, the motor structure includes the upper diaphragm casing 7 and a similarly or symmetrically conformed lower diaphragm casing 8 which casings are formed with the lateral flanges 7' and 8' respectively. A diaphragm 9 is secured between the flanges by suitable means such as the bolts 10. The diaphragm may be composed of any suitable, flexible, gas-impermeable material such as the rubberized fabric commonly employed in the art. The attached upper and lower casings with the intermediate diaphragm thus define, in effect, two pressure chambers, namely, an upper chamber 11 and a lower chamber 12 to which fluid, such as air, may be admitted to apply a variable pressure on either the upper or lower face of the diaphragm.

The upper diaphragm casing is formed with the port or aperture 13 registering axially with the bore of a pipe fitting 14. Similarly, the lower diaphragm casing is provided with the port 15 in communication with the lower pipe fitting 16. The pipe fittings may be attached to their respective casing members in any suitable manner, preferably by weld joints.

The diaphragm 9 is connected to the diaphragm stem 2 in any suitable manner so as to impart reciprocating motion to the latter upon applied flexure of the diaphragm. As shown, the diaphragm is associated with the upper pressure plate 17 and the lower pressure plate 18. These are centrally apertured to receive the reduced end section 19 of the diaphragm stem. As will be observed, the motor stem 2 is reduced at 19 to establish the shoulder 20 and is also reduced a short distance below shoulder 20 to provide the second shoulder 21. The shoulder 20 is adapted to directly abut the lower pressure plate 18. The pressure plates are held in firm attach-

ment to the shaft and diaphragm by means of the nuts 22.

The spring barrel 3 is somewhat reduced in internal diameter at its upper section to provide a slightly enlarged bore and to establish a shoulder or abutment 23. This reduced bore section is also cut away to provide the groove 24 for the reception of the split spring locking ring 25. A spring button or bridge 26 is fitted into the upper section of the spring barrel so that its lower peripheral edge engages the abutment 23. The bridge is centrally apertured and is fitted with the guide bushing 26'. The bridge is formed with the depending boss 27 which functions to retain spring 2 in proper position. The upper face of the member 26 is cut away to provide the peripheral groove 28 in which is mounted a compressible sealing member such as the ring 29 composed of neoprene or other elastomeric material. As will be observed, the bridge 26 functions as a guide for the stem 2 and as a thrust abutment or button for the spring 4. The boss 27 serves to center the spring in proper axial position.

The spring button 26 is maintained in assembled position in the barrel by means of the centrally apertured retainer disc 30. As will be seen, this disc fits snugly within the enlarged bore section of the spring barrel and is locked in its operative position by means of the locking ring 24. In assembling the superstructure the disc 30 is forced downwardly to compress the ring 29 thus establishing an effective air seal between the barrel on the one hand, and bridge 26 and disc 30 on the other.

As indicated previously, the invention basically comprehends the concept of establishing a seal of maximum gas-impermeability coupled with minimum physical inertia between the diaphragm chamber and the reciprocating stem to thereby positively insure a high sensitivity of response of the valve element to very small changes in air pressure on the diaphragm. This is achieved by utilizing a special bellows seal and appropriately associating it with the diaphragm on the one hand, and the spring barrel on the other, so that the sealing or pressure retention function does not involve any frictional pressure contact on the reciprocating stem.

The improved bellows or Sylphon seal is shown in detail in Fig. 2. This comprises the tubular corrugated member 31 which is composed of suitable gas-impermeable material such as rubber, or other equivalent elastomers, or a light, strong fabric coated, saturated or impregnated with an elastomeric material such as neoprene. Such material is impermeable to gases and is essentially flexible or flaccid and therefore may be extenuated or convoluted with the minimum application of force. Since this material is highly flexible it is inherently non-sustaining and therefore it is desirable to provide a supporting structure which will retain the material in the desired tubular corrugated shape. This is accomplished by associating a helical spring 32 with the tubular fabric. As will be appreciated, the essential function of the spring is to maintain the gas-impermeable extensible tube 31 in the desired tubular shape; hence, the spring need only be of relatively small cross-section and of low tension. It is apparent however that, if desired, the tension of the spring may be beneficially invoked to increase the sensitivity of the unit by utilizing it to compensate for and, to a degree, balance the weight of the diaphragm and pressure plates

thus rendering the valve more accurately and immediately responsive to changes in pressure of the controlling fluid admitted to a diaphragm chamber.

As shown, particularly in Fig. 1, the fabric 31 extends beyond the upper and lower convolution of the sustaining spring 32. The upper extension of the fabric is adapted to be attached to a part associated with the movable diaphragm and the lower extension, conversely, is adapted to be secured to the disc 30. The upper anchorage for the bellows seal comprises the centrally apertured disc or button 33. This, as will be noted, embraces the upper reduced section of stem 2 between shoulders 26 and 24. The inner face of the disc 33 is formed with a groove in which the neoprene sealing ring 34 is fitted to thereby establish a fluid tight seal between the stem 2 and the disc. The lower face of the disc is cut out, along its periphery, to form the peripheral groove 35 which receives the upper or terminal convolution of spring 32 and which also serves to center such spring in proper axial alignment in the assembled unit.

The fabric 31 is extended upwardly beyond the upper convolution of the spring and more or less tightly contacts the vertical face of the disc 30. A pressure tight fit between the bellows and disc may be attained by cementing the fabric extension 36 directly to the vertical face of the disc 33, or, alternatively, by utilizing a clamping ring (not shown) to firmly anchor the fabric extension to disc 33.

The lower portion of the flexible corrugated low inertia tubing is similarly attached to disc 30 to thereby establish an effective gas pressure seal between the diaphragm chamber and the spring barrel. As shown, the tubular fabric 31 is extended below the last or the lower convolution of the spring 32 and is adapted to snugly engage the shoulder 36 formed on the disc 30. The fabric may be attached to the disc by directly cementing it thereto or by means of a clamping ring or by a combination of these two expedients. As will be observed, the disc 30 is formed with the peripheral groove 37 adapted to receive the terminal convolution of the sustaining spring 32.

The effective functioning of the seal structure will have been appreciated from the foregoing description. It is apparent that by reason of the interposition of the novel sealing means between the reciprocating diaphragm and the spring barrel, permitting free low inertia extenuation of the sealing means, the diaphragm itself is thus made responsive to minor increments of pressure applied by introduction of controlling fluid to the diaphragm chamber. Since low frictional tolerances are established between the diaphragm stem 2 and the disc 30 and bridge 26 each increment of applied fluid pressure, however slight, is immediately translated into axial displacement of the shaft 2.

The lower end of the diaphragm stem 2 is guided in its reciprocating motion by the lower bridge 40. This is assembled in the spring barrel at the lower portion thereof and may be attached to the barrel in any suitable manner, preferably by a circumferential weld joint, at the lower interface between the bridge and the barrel. As shown, the bridge 40 is formed with the boss 41 which serves as a centering means for the spring 2 when the unit is assembled for operation as a direct acting valve. Close guiding tolerances for the stem 2 are established by utilizing a low fric-

tion bushing 42. Preferably this bushing is swedged or otherwise secured to the stem 2. In the preferred construction the member 42 comprises a porous oil impregnated bushing adapted to reciprocate within the bore of the lower bridge 40 with the minimum possible friction.

As has been indicated previously, the diaphragm stem 2 is adapted to be connected to a valve stem which latter is directly connected to a reciprocating valve. As shown in Fig. 1, such valve stem 43 is formed with a reduced tapered end section fitting within a bore 44 tapped in the main diaphragm stem 2. The main diaphragm stem 2 may be connected to the valve stem 43 in any suitable manner, for example, as shown in the drawings, by means of a taper pin 45 driven through the connecting nut 46 to thereby establish a direct reciprocating connection between the diaphragm and the valve stem. As will be appreciated, in lieu of such simple connection any other means of attaching the valve stem to the diaphragm stem 2 may be utilized.

As illustrated, the diaphragm stem is of reduced diameter in its median and lower section and such reduced section is fitted with the sleeve 47. This may be keyed, swedged or otherwise attached to the main stem 2 and is exteriorly threaded to receive the spring adjusting element such as the serrated nut 48. Interposed between the adjusting nut 46 and the spring 2 is a spring thrust button 49. As shown, this is formed with a lower substantially conical surface contacting the upper conoidal surface of adjusting nut or button 46. The spring thrust button 49 is formed with the central boss 49 to receive and center the spring 4.

The yoke section 5 is formed with a suitable aperture 50 to permit ready access to the nut 46 for connecting and disconnecting the valve stem 43. The spring barrel 2 similarly is formed with slots or other form of apertures 51 and 52 to permit the insertion of tools such as a spanner or screw driver to adjust the position of the nut 46 to thereby vary the tension of spring 4 to any desired degree. These apertures also allow the insertion of a tool to forcibly elevate or depress the stem 2 to free a valve plug which may become locked to its seal by the accumulation of solid deposits or the like.

A salient feature of the invention, as previously pointed out, is that it establishes an effective highly sensitive motor valve construction which is standardized for use optionally with direct or reverse acting valve units. The turret top construction is as efficient as it is esthetic in its balanced symmetry. Such a standard superstructure manifestly insures more economical factory production and most importantly makes it possible to convert from a reverse acting to a direct acting valve in the field.

The unit shown in the drawings, as will be apparent, is adapted to be connected to a reverse acting valve through connection with the valve stem 43. For such a purpose the variable fluid pressure medium is connected to the unit through the lower pipe fitting 16. In these circumstances the pressure of the control fluid acts on the lower surface of the diaphragm tending to elevate the diaphragm stem and its connected valve stem 43. The spring 4 conversely urges the stem 2 downwardly in opposition to the applied fluid pressure.

Such a unit may readily be converted so as to function equally effectively with a direct acting valve unit. This may be readily achieved by dis-

mantling the unit and rearranging the position of spring 4, the spring thrust button 48 and its associated nut 46. In such newly assembled position for functioning as a direct acting valve the lower convolution of spring 4 then abuts the upper face of bridge 40 and the thrust button 48 and adjusting nut 46 occupy a position near the upper end of sleeve 47 and about opposite the slot 52. The source of the controlling fluid pressure is then connected to the upper diaphragm chamber 11 through fitting 14. It will be seen that the unit is designed so as to facilitate such a conversion. This may readily be done by removing the upper diaphragm case 7 and unlocking the locking or retainer ring 25. Upon disconnecting the valve stem 43 and removing the nut 46 the stem 2 with the attached nut 46 and the upper rings 26 and 38 may be removed from the spring barrel after which the position of the thrust ring 48 and nut 46 is changed as previously described.

It will be evident that the improved diaphragm valve construction may be adapted for use with rotary as well as reciprocating valve elements. This may be done by translating the reciprocating motion of diaphragm stem 2 to rotary motion by suitable means and utilizing such rotary motion to actuate a rotary valve.

It will be observed that the unit is of simplified design and of sturdy construction. The unit may be fabricated largely from machined bar stock thus insuring high structural strength coupled with optimum dimensional tolerances. It will now be appreciated that the invention presents manifold advantages including simplicity of construction, facile conversion in the field and a unit which is as essentially rugged as it is sensitive. While a preferred modification of the invention has been described it is to be understood that this is given didactically to exemplify the underlying principles of the invention and not as limiting its useful scope except as such limitations are clearly imposed by the appended claims.

I claim:

1. A diaphragm valve superstructure which comprises, a diaphragm casing having a flexible diaphragm mounted therein, a stem connected with the diaphragm and movable therewith, a spring barrel secured to the diaphragm casing, a stem guide and spring abutment assemblage mounted at each end of the barrel, a spring enclosing the stem having one end contacting one spring abutment assemblage and the other end contacting a part adjustably movable axially on the stem and means to establish a fluid tight seal between the diaphragm casing and the stem including, a flexible, tubular, non-metallic bellows attached respectively to the said assemblage at the upper end of the barrel and to a movable part associated with the diaphragm.

2. A diaphragm valve superstructure which comprises, a diaphragm casing having a flexible diaphragm mounted therein, a stem connected with the diaphragm and movable therewith, a spring barrel secured to the diaphragm casing, a stem guide and spring abutment assemblage detachably mounted in the upper section of the barrel, a spring enclosing the stem having one end contacting the said assemblage and the other end contacting a part adjustably movable axially on the stem, and means to establish a fluid tight seal between the diaphragm casing and the stem including a flexible, tubular, non-metallic bellows attached respectively to the said assemblage and to a movable part associated with the diaphragm.

3. A diaphragm valve superstructure which comprises, a diaphragm casing having a flexible diaphragm mounted therein, a stem connected with the diaphragm and movable therewith, a spring barrel secured to the diaphragm casing, a stem guide mounted in the upper section of the barrel, a stem guide mounted in lower section of the barrel, a spring enclosing the stem having one end contacting one of said stem guides and the other end contacting a part adjustably movable axially on a portion of the stem and means to establish a fluid tight seal between the diaphragm casing and the stem including a flexible, tubular, non-metallic bellows attached respectively to the upper stem guide and to a movable part associated with the diaphragm.

4. A diaphragm valve superstructure which comprises, a diaphragm casing having a flexible diaphragm mounted therein, a stem connected with the diaphragm and movable therewith, a spring barrel secured to the diaphragm casing, an upper stem guide detachably mounted in the upper section of the barrel, a spring enclosing the stem having one end contacting the said upper stem guide and the other end contacting a part adjustably movable axially on the lower portion of the stem and means to establish a fluid tight seal between the diaphragm casing and the stem including a flexible, tubular, non-metallic bellows attached respectively to the upper stem guide and to a movable part associated with the diaphragm.

5. A motor valve superstructure which comprises, a diaphragm casing having a flexible diaphragm mounted therein, and defining an upper and lower pressure chamber, a fluid inlet connected with each chamber, a stem connected with the diaphragm and movable therewith, a spring barrel secured to the diaphragm casing, a stem guide and spring abutment assemblage detachably secured to the upper portion of the barrel and forming a pressure tight seal therewith, a stem guide unit mounted in the lower section of the barrel, a spring adapted to enclose the stem, said stem guide being provided with means at its upper and lower sections to receive an abutment, a spring abutment adapted to be adjustably attached to an upper or a lower section of the stem such that the spring may be mounted between the upper spring abutment and the adjustable spring abutment mounted on the lower section of the stem or between the lower stem guide and the adjustable spring abutment adjustably mounted on the upper section of the stem, means to establish a fluid tight seal between the diaphragm stem and the diaphragm casing including a flexible, tubular, non-metallic bellows attached respectively to the said assemblage and to a movable part associated with the diaphragm.
